MEANS FOR CARRYING COILS OF WIRE OR
TAPE-SHAPED BODIESSemi Begun, Berlin, Germany, assignor to C.
Lorenz Aktiengesellschaft, Berlin-Tempelhof,
Germany, a companyApplication June 6, 1935, Serial No. 25,355
In Germany July 5, 1934

4 Claims. (Cl. 206—53)

The invention has for its object to prevent wire- or tape-shaped means, coiled on a spool, drum or the like, from uncoiling and is especially useful on the transportation of such spools and if the wire- or tape-shaped body is rigid to some extent or resilient so as to be liable to uncoil, as are for instance the steel tapes or wires of electromagnetic talking machines of the Poulsen type.

With this object in view, the subject of the invention is a device adapted to be fastened to the spool as well as to the free end of the coiled body.

One embodiment of the invention is described hereafter, reference being had to the accompanying drawing in which

Fig. 1 is an elevation, while Fig. 2 represents a section on the line A—B of Fig. 1.

The spool 1 shown by way of example is of the type employed in electromagnetic talking machines wherein such spools are to carry a steel tape or wire as a sound record carrier, a tape 2 being shown in the case here represented.

For the purpose of the invention a circular groove 3 is provided in either face of the spool 1. These grooves are to receive the ends of a spring clip 4 to which a block 5 is secured, as will be seen from Fig. 2. Block 5 has a recess 6 which is to receive the free end of the tape 2. This tape end is clamped fast by means of a screw 7 whose thread is in engagement with a female thread of the block 5. The screw 7 may be fitted with a check nut 8.

The clip 4 can thus in each case be so adjusted along the circumference of the spool that the tape shall be under tension.

What is claimed is:

1. A device for fixing a resilient wire coiled on

a rigid spool, which comprises a spring clip adapted to be clamped to the outside of the spool and displaceable around the circumference thereof, and wire holding means including a clamping screw through which the wire is displaceable and in which the wire may be fixed by said clamping screw. 5

2. For carrying resilient wire or the like, the combination of a spool provided with a circular groove in at least one face and a substantially U-shaped spring clip clamped to said spool and displaceable around the circumference thereof, said clip having an edge or blade engaging said circular groove for securing the clip to the spool and having a wire holding portion provided with 15 screw clamping means, the wire being displaceable through said portion and the screw clamping means being adapted to fix the wire in said portion.

3. For carrying a coiled resilient steel wire or 20 the like the combination of a spool having in one face a circumferential groove, and a clip having means for engaging the free end of said wire, said clip being adjustable along the circumference of the spool and having a bent portion 25 extending parallel to the axis of the spool into said groove and fitting closely in said groove so as to resist rotation of said portion relative to said groove.

4. An arrangement for storing stiff springy 30 wire or the like which comprises a spool upon which the wire is coiled, having a groove, in combination with a clip engaging said groove and attached to the wire at such an angle that the wire is comparatively sharply flexed in the vicinity of said attachment point. 35
